ABSTRACT

An electromagnetic vibrator wherein the armature is coupled to and supported on its associated mass by means of an adjustable coupling arrangement so that the armature and its mass are spaced from one another. A central disc spring element is arranged between the armature and the associated mass to bias these elements away from each other with a force sufficient to prevent relative movement between the armature and its associated mass. One or a plurality of disc springs may be used, and a guide means is generally provided on the mass for positioning the spring or springs. By adjusting the coupling means, and consequently the bias face exerted by the disc spring, the space between the armature and its associated mass is varied which simultaneously varies the operational air gap of the vibrator between the armature and its associated core.

ELECTROMAGNETIC VIBRATOR

CROSS-REFERENCE TO RELATED APPLICATION

This application is a continuation-in-part application of applicants' copending U.S. application Ser. No. 88,665, filed Nov. 12, 1970 now abandoned.

BACKGROUND OF THE INVENTION

The present invention relates to an electromagnetic vibrator for driving vibrating conveyors, the vibrator including two oppositely vibrating masses coupled by springs whose vibrations are produced by an electromagnet excited by an alternating current of constant frequency. The vibration producing forces are produced between two parts of an electromagnetic core associated with the two oppositely vibrating masses, which core portions are subjected to periodic mutual attraction in dependence on the current.

The adjustment of the air gap existing between the two core portions is of extraordinary importance for the economic operation and functionability of the drive. If the air gap is set too large, the reactive power demands of the electromagnet is raised beyond proportion, thus having an adverse effect on the energy source as well as on the current-dependent heating of the windings of the electromagnet.

On the other hand, the air gap must be selected to be sufficiently large to prevent the vibrating masses from colliding even during the slightest operational irregularities — as, for example, a change in the mass conditions by a different specific weight of the materials to be conveyed, or at the beginning of clogging in the conveying trough. Such collisions would lead to heavy damage in a very short time and eventually to complete destruction. An optimum and exact air gap adjustment according to the above considerations is, thus, of utmost importance. At present, however, because of the individual differences in different vibrators, this adjustment can be made only by measuring the vibration amplitudes in the test field of the finished vibrator.

It is known, for example, to insert elastic members between the magnetic armature and its supporting component to prevent the two vibratory masses from colliding. These elastic members are substantially deformed when the magnetic armature and the magnetic core collide, but practically no deformation of the elastic members occurs during normal vibratory movement. One embodiment has small disc springs inserted at the fastening bolts between the magnetic armature and the free mass. This arrangement, however, requires a large amount of space in its lateral expanse. Moreover, the small disc springs exhibit only a very short deflection path.

SUMMARY OF THE INVENTION

An object of the present invention is to provide an electromagnetic vibrator that overcomes the problems set out above.

A substantial saving in space and a sufficient deflection path for setting the air gap, as well as presenting the possibility of being able to set the air gap successively during the testing operation, is provided by a vibrator according to the present invention in which a central disc spring element is clamped between the armature and its associated mass, the bias of this disc spring element determining the spacing of the armature and its associated mass and thus setting the operational

air gap of the vibrator between the armature and the core.

BRIEF DESCRIPTION OF THE DRAWINGS

FIGS. 1 and 2, are schematic, elevational views of electromagnetic vibrators according to the prior art which illustrates two different methods of mounting the armature for movement relative to the core and for setting the air gap.

FIGS. 3a and 3b are a side view and a sectional end view respectively of a portion of an electromagnetic vibrator according to the prior art showing an arrangement for adjustably connecting the armature to its associated mass so that the operational air gap of the vibrator can be adjusted.

FIG. 4 is an elevational view of a portion of an electromagnetic vibrator according to the prior art showing an alternative arrangement for adjustably connecting the armature to its associated mass so that the operational air gap of the vibrator can be adjusted.

FIG. 5a is a side cross-sectional view taken generally along the line 5a-5a of FIG. 5b.

FIG. 5b is a top plan view of one embodiment of an arrangement according to the present invention for adjustably connecting the armature of an electromagnetic vibrator to its associated mass.

FIGS. 6 and 7 are side cross-sectional views of further embodiments according to the present invention of an arrangement for adjustably connecting the armature of an electromagnetic vibrator to its associated mass.

FIG. 8a is a side cross-sectional view taken generally along the line 8a-8a of FIG. 8b.

FIG. 8b is a top plan view of still another embodiment according to the present invention of an arrangement for adjustably connecting the armature of an electromagnetic vibrator to its associated mass.

FIG. 9 is a sectional view of an electromagnetic vibrator of the type schematically shown in FIG. 2 with the armature connecting arrangement according to the invention shown in FIG. 5.

FIG. 10 is a partial sectional view of an electromagnetic vibrator of the type schematically shown in FIG. 1 with the armature connecting arrangement according to the invention shown in FIG. 8.

DESCRIPTION OF THE PREFERRED EMBODIMENTS

Many solutions are known for setting the air gap in an electromagnetic vibrator. FIGS. 1 through 4 of the drawings show several examples of known solutions.

In FIGS. 1 and 2, which illustrate a helical spring and leaf spring vibrator respectively, the air gap (indicated by the opposed arrows) of the electromagnet is set by adjustment at the contact points of the mass coupling springs, for example as shown in FIG. 2 by the supports 10. In these known arrangements, the air gap can be set only as a whole — i.e., in one direction — and consequently if the border surfaces of the air gap are not parallel to one another, no alignment can be made.

It is also known to adjust the air gap between the core and armature of a vibrator by fastening the armature to its associated mass by means of bolts which cooperate with longitudinal holes in the armature, as shown in FIGS. 3a and 3b, or by means of nuts and lock-nuts on specially attached spacer studs, as shown in FIG. 4. The use of the longitudinal holes (FIG. 3) does not seem to

be sufficiently dependable in the long run, because of the vibrations and shaking forces, whereas the use of bolts with nuts and lock-nuts (FIG. 4) requires a relatively large area for their installation. This is uneconomical in small vibrators due to the high weight to horsepower ratio.

In each one of the known constructions described above the vibrator drive must always be de-energized when the air gap is to be adjusted, because only in the rest state can the clamping elements be handled. The air gap adjustment thus constitutes a time-consuming "testing," or trial-and-error procedure, until the optimum setting has been found.

FIGS. 5a and 5b show an embodiment of the present invention in which a large, centrally located disc spring 3, constructed from a suitable, known material, is inserted between the four setting bolts 4 arranged in the four corners of the armature coupling piece 1 of the free mass of the vibrator and an armature 2 to hold together the coupling piece 1 and the armature 2.

If the spring force of one disc spring by itself is not sufficient, two disc springs 3 can be disposed, as shown in FIG. 6, in an opposed relationship; for example, in series. If the spring force is insufficient — for example, if natural vibrations develop between the free mass 1 and the armature 2 — two or more disc springs may be connected in the same direction; that is, in parallel. FIG. 7 shows a pair of two parallel connected disc springs arranged in series.

As a guide for one or a plurality of springs, a central cylindrical guide 6,6',6" protrudes from the coupling piece 1 (FIGS. 5,6 and 7). The embodiments of FIGS. 6 and 7 have a corresponding recess 7 disposed in the armature 2 opposite this guide so that the guide can move into this recess when the springs are pressed together.

It is, however, also possible to guide one or a plurality of springs 3' along the external diameter by means of a centrally located, cylindrical recess 8 in the coupling piece 1 (FIGS. 8a and 8b).

Referring now to FIG. 9 there is shown an embodiment of a leaf spring type vibrator incorporating the armature mounting arrangement according to the invention. The vibrator includes a stand or base 11 in which is mounted an open core 12 with electrical windings 13 about the poles thereof. The core 12 and windings 13 are fastened to the base 11 by means of bolts 15 and preferably are also encased in a casting resin 14.

The base 16 is provided with a pair of upwardly extending arms 16. Fastened to the top of these arms 16 by means of bolts 17 are the respective ends of the leaf springs 18 which provide the vibratory motion of the vibrator.

The free mass of the vibrator, which includes a weight portion 20 and the armature coupling piece 1, and the core armature 2, which is fastened to the coupling piece 1 by means of bolts 4, are attached to the center of the leaf springs 18 by means of one or more bolts 19. According to the illustrated embodiment of the invention, a single cup spring 3 is clamped between the armature coupling piece 1 and the core armature 2. The degree of pretensioning or biasing force exerted by the spring 3 is determined by the setting of the screws 4 by means of which the air space 21 between the armature coupling piece 1 and the armature 2 can be adjusted. Adjusting the air space 22 simultaneously adjusts and sets the operating air gap 22 between the

armature 2 and the pole surfaces of the open core 12.

FIG. 10 illustrates the armature mounting arrangement according to the present invention whereby the operational air gap may be set by means of a cup spring 3 for a vibrator employing helical springs 23 for providing the vibrator motion. In this type of vibrator the edge of the weight portion 20 of the free mass serves as an abutment for the helical springs 23 and the free mass is guided at each end by a long continuous bolt 24 which is fastened to the supporting frame or base 11.

The operation of the present invention can be clearly seen in the two drawings.

Tightening of bolts 4 against the pressure of cup spring 3 causes the distance 21 between the armature support or coupling piece 1 and the armature 2 to be reduced, so that the operating air gap 22 between the armature 2 and core 12 is increased and vice versa.

The present invention permits the continuous setting of the desired operating air gap without any complicated installation work. That is with the arrangement of the present invention, the operating air gap 22 can be adjusted merely by tightening bolt 4 even during operation, so that the field test operations require only a fraction of the time required for the known methods. Moreover, since the adjustment of the air gap is accomplished solely by adjusting the position of the armature 2 relative to the coupling piece 1 of the free mass, the pretensioning of the operating springs required for the vibration, i.e., the springs 18 or 23, is in no way effected by the setting of the air gap.

Of course, a prerequisite for proper functioning of the invention is that bolts 4 remain in the set position and can not yield during operation. If the thread bores for holding the bolts 4 are directly placed in a known laminated armature, the seat for the bolts is naturally extremely tight. A further improvement is realized when oversize bolts are used, for example with a particularly heavy, known, electrolytic protective coating.

Other possibilities are to insert a known synthetic resin adhesive into the threads, which hardens some time after the completed adjustment and which produces a practically unseparable connection between the bolts and the thread bore.

Or, further thread bores which are arranged transverse to the first thread bores, such as shown in FIGS. 6 and 7 and designated by the reference numeral 5, can be provided with which the sheets of a laminated armature 2 (laminations not shown) are clamped together, thus clamping in setting bolts 4. The laminations are, of course, parallel to the plane of the paper in FIGS. 6 and 7.

It will be understood that the above description of the present invention is susceptible to various modifications, changes and adaptations, and the same are intended to be comprehended within the meaning and range of equivalents of the appended claims.

We claim:

1. In an electromagnetic vibrator including an armature, the improvement comprising:
  - a mass associated with said armature and spaced therefrom to define an air space therebetween;
  - adjustable means coupling said mass to said armature; and
  - a centrally located disc spring means arranged between said armature and said associated mass and exerting a sufficient force for biasing said armature and associated mass so that, in cooperation with

said adjustable coupling means, a desired air space setting is maintained between said armature and said associated mass and said armature and said associated mass move as a unit during vibration of the vibrator, whereby by adjusting said coupling means, said air space and consequently the operational air gap of said vibrator adjacent said armature is adjusted without affecting the vibrating characteristics of the vibrator.

2. An electromagnetic vibrator as defined in claim 1, wherein said disc spring means has at least two oppositely directed and contacting disc springs.

3. An electromagnetic vibrator as defined in claim 2, wherein said disc spring means is a plurality of disc springs arranged in a combination of oppositely directed springs and same directed springs.

4. An electromagnetic vibrator as defined in claim 3, wherein at least two contacting disc springs are arranged in the same direction.

5. An electromagnetic vibrator as defined in claim 4, wherein one of said armature and said associated mass defines a guide means for said spring means.

6. An electromagnetic vibrator as defined in claim 5, wherein said guide means is a centrally located, cylindrical member protruding from said associated mass.

7. An electromagnetic vibrator as defined in claim 6, further including a recess defined in said armature for receiving said member.

8. An electromagnetic vibrator as defined in claim 5,

10

wherein said guide means is a centrally located, cylindrical recess defined in said associated mass and configured to receive at least one of said disc springs.

9. In an electromagnetic vibrator including a magnetic armature mounted for vibratory movement relative to a magnetic core, and a free mass associated with said armature, the improvement comprising:

an adjustable means for coupling said armature to said mass so that said armature is adjustably displaceable relative to said free mass in the direction of the vibratory movement of the vibrator; and a centrally located disc spring means arranged between said armature and said free mass for biasing said armature and said free mass apart to provide an air space therebetween, said spring means exerting a sufficient force so that said armature and said associated mass move as a unit during vibration of the vibrator, whereby adjustment of said coupling means varies the position of said armature relative to said mass and thereby the operational air gap of said vibrator between said armature and said core.

10. The electromagnetic vibrator as defined in claim 9 wherein said adjustable coupling means comprises an armature coupling piece which forms part of said mass and which extends parallel to the plane of said armature, and a plurality of bolts extending through openings in said coupling piece and threadingly engaging said armature.
